US00D836101S

(12) **United States Design Patent** (10) Patent No.: **US D836,101 S**
(45) Date of Patent: **** Dec. 18, 2018**

(54) **ELECTRONIC DEVICE**

- (71) Applicant: **Samsung Electronics Co., Ltd.**, Suwon-si (KR)
- (72) Inventors: **Yongseok Bang**, Yongin-si (KR); **Miri Lee**, Namyangju-si (KR); **In Sik Chung**, Seoul (KR); **Jaehyung Hong**, Seoul (KR)
- (73) Assignee: **SAMSUNG ELECTRONICS CO., LTD.**, Suwon-si (KR)
- (**) Term: **15 Years**
- (21) Appl. No.: **29/627,871**
- (22) Filed: **Nov. 30, 2017**

Related U.S. Application Data

- (63) Continuation of application No. 29/542,451, filed on Oct. 14, 2015, now Pat. No. Des. 807,352.

(30) **Foreign Application Priority Data**

- Aug. 13, 2015 (KR) 30-2015-0041028
- (51) **LOC (11) Cl.** **14-02**
- (52) **U.S. Cl.** **D14/344**

(57) **CLAIM**

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof; and,

FIG. 9 is a front perspective view thereof, in which a wristband in dashed broken lines is provided to depict an example environment.

The dashed broken lines, showing portions of the electronic device in the figures and the wristband in FIG. 9, form no part of the claimed design.

1 Claim, 9 Drawing Sheets
